INFANT'S ATTACHABLE CHAIR

Lothar T. Buehler and Elmer W. Buehler,
Milwaukee, Wis.

Application February 24, 1948, Serial No. 144,704

Term of patent 7 years

(Cl. D15—8)

To all whom it may concern:

Be it known that we, Lothar T. Buehler and Elmer W. Buehler, citizens of the United States and residents of Milwaukee, in the county of Milwaukee and State of Wisconsin, have invented a new, original, and ornamental Design for an Infant's Attachable Chair, of which the following is a specification, reference being had to the accompanying drawing, forming part thereof.

Fig. 1 represents a side elevation of an infant's attachable chair, embodying the features of our invention.

Fig. 2 is a front elevational view of the same.

Fig. 3 is a top plan view of the same.

Fig. 4 is a rear elevation of said chair, and

Fig. 5 is a bottom plan view of the same.

We claim:

The ornamental design for an infant's attachable chair, as shown.

LOTHAR T. BUEHLER.
ELMER W. BUEHLER.
